FRANK B. COMINS, OF NEWTON, MASSACHUSETTS, ASSIGNOR TO AMERICAN MOISTEN-
ING COMPANY, OF BOSTON, MASSACHUSETTS, A CORPORATION OF MAINE.

MOISTURE-CONTROLLING DEVICE.

1,410,999.

Specification of Letters Patent. Patented Mar. 28, 1922.

Application filed April 24, 1919. Serial No. 292,359.

To all whom it may concern:

Be it known that I, FRANK B. COMINS, a citizen of the United States, residing at Newton, in the county of Middlesex and State of Massachusetts, have invented certain new and useful Improvements in Moisture-Controlling Devices; and I do hereby declare the following to be a full, clear, and exact description of the invention, such as will enable others skilled in the art to which it appertains to make and use the same.

The present invention relates particularly to moisture controlling devices of the type employing a psychrometer, although certain features of the invention are also applicable to various other devices.

Controlling devices of this type have been designed in such manner that both the indicating and controlling instruments thereof are located necessarily in the room in which it is desired to regulate and control the atmospheric condition. Such controlling devices have certain instruments which must be readily accessible for the purposes of observation and manual control which in case of the prior devices, necessitates the attendant entering the room from time to time. Consequently, while such prior controlling devices are satisfactory for use in a room of moderate temperature, they are obviously impracticable for use in a drying or other conditioning room which is maintained at such a high temperature that it could not be entered with safety. It is, therefore, most desirable that a controlling device of this type be constructed such that the indicators and manually controllable instruments shall be conveniently accessible outside of the conditioning room. Heretofore, however, it has been an unsolved problem to produce a satisfactorily working controlling device of this desired construction, the main difficulty being to maintain the wet bulb element of the psychrometers in the desired constant state of saturation.

These wet bulb elements comprise a wick which passes over a thermostatic cylinder, and the only known satisfactory manner of supplying moisture to the wick is by capillary attraction from liquid contained in a closed container in which is created a partial vacuum. The liquid containers have been constructed heretofore in such manner that in order to obtain the desired degree of vacuum therein, it is necessary to remove

them from the controlling devices and place them in an inverted position while being supplied with liquid which, of course, necessitates the attendant entering the conditioning room.

One of the objects of the present invention is to provide a novel and improved controlling device of the type above indicated which is constructed and arranged so that both the indicating and manually controllable instruments may be conveniently accessible outside of the conditioning room.

Another of the objects of the present invention is to provide a novel and improved moisture supplying device.

A feature of the present invention contemplates the provision of a moisture absorbing element connected with a liquid container and means for supplying liquid to the container and creating a partial vacuum therein without disturbing the normal position thereof whereby the moisture absorbing element is maintained in a constant state of saturation. In the preferred application of the invention the moisture absorbing element constitutes a wick of the wet bulb element of a psychrometer although, except as defined in the claims, the invention is not limited to this specific application. Preferably, the liquid is supplied to the liquid container, and air is simultaneously expelled from the container through conduits connected therewith which are controlled by a manually operable valve. When the invention is embodied in a controlling device, the valve may be conveniently located outside of the conditioning room.

Other features of the present invention comprise certain constructions, arrangements and combinations of parts hereinafter described and claimed, the advantages of which will be obvious to those skilled in the art.

The several features of the present invention will be readily understood from the following description and accompanying drawings in which: Figure 1 is a front elevation of a controlling device comprising the features of the invention in their preferred form; Fig. 2 is a side elevation of the controlling device with a portion of the wall of a room shown in section; Fig. 3 is a vertical sectional view, mostly in elevation, taken on the line 3-3 of Fig. 2; Fig. 4 is a detail side elevation, on an enlarged scale, of the liquid container and certain parts of the de-

vice connected therewith and showing the wet bulb element in section; and Fig. 5 is a detail sectional view, on an enlarged scale, taken on the line 5—5 of Fig. 4.

5 The controlling device illustrated in the drawings comprises a front instrument supporting plate 2 which closes an opening 4 in a wall of the conditioning room, a rear instrument supporting plate 6, and side frames 10 8 which connect said plates. The front plate 2 is provided with an opening normally closed by a door 19, through which access may be had to the instruments located within the room. The door is provided with a 15 glass window through which the instruments may be observed without opening the door. A psychrometer 10 is mounted on the forward side of the rear plate 6 which, through mechanism well known to those skilled in 20 the art, controls the opening and closing of heat and humidity diaphragm valves 16 and 18, respectively, mounted on the front plate 2. Also mounted on the front plate 2 are the gages 20 and 22 which indicate the 25 conditions of the valves 16 and 18 respectively. The psychrometer 10 comprises dry and wet bulb elements 24 and 26, respectively, and an indicator 28. The wet bulb element of the psychrometer comprises the usual cylinder 30 over which passes a wick 32, the lower end of which extends through an opening in a cylindrical trough 34 to which water is supplied through a pipe 36. In order to insure a 35 thorough saturation of the wick 32, a member 38 attached to the upper end thereof extends through a pipe 40 to the pipe 36. A wet bulb thermometer 42 mounted on the rear plate 6 is connected by a wick 44 to the cylindrical trough 34. The pipe 36 is provided with a valve 46 having an elongated 40 stem 48 which extends through the front plate 2 and is provided with a knob or handle 50. The pipe 36 leads to a water tank or container 52 mounted on the rear side of the rear plate 6. The upper portion of the tank 52 is connected by a water supply pipe 54 to a 45 suitable source of water supply and is provided with a compound valve 56 conveniently located adjacent the front side of the plate 2. An air vent pipe 58 also leads from the upper portion of the tank 52 to the compound valve 56. By means of the valve 56 the pipes 54 and 58 may be simultaneously 50 opened and closed, the air vent 58 opening 55 into the atmosphere when the valve is open. The valve 56 comprises a casing 60 and a rotary tapering spigot or plug 62 which may be actuated by means of a handle 64. The rear end of the plug 62 of the valve is provided with an axial bore 66 leading from the atmosphere to a radial bore 68 extending to the valve casing, the outer end of which is in the vertical plane of an opening 70 in the casing into which the air vent pipe 58 extends. When the valve is opened, the pas-

sage formed by the bores 66 and 68 in the plug 62 is brought into registry with the air vent pipe 58.

To fill the container 52 with water in such manner that the wick of the wet bulb element 26 will be maintained in a constant state of saturation, the shut-off valve 46 is closed by means of the handle 50 at the front of the plate 2. The compound valve 56 is then opened to permit water to be supplied to the container. As the water rises in the container, the air is expelled therefrom through the air vent pipe 58. The completion of the filling of the container with water is indicated by water flowing out of the air vent passage in the plug 62 of the valve, at which time the valve 56 may be closed. When the shutoff valve 46 is opened, water will be caused to flow through the pipe 36 and into the cylindrical trough 34, which will cause a partial vacuum to be created in the container. Moisture will then be supplied to the wick of the psychrometer to the same extent as moisture is removed therefrom by evaporation. It will be noted that by this construction water may be supplied to the container and a partial vacuum created therein by the manipulation of means located outside of the conditioning room.

The nature and scope of the present invention having been indicated and a device embodying the several features of the invention in their preferred form having been specifically described, what is claimed is:

1. A moisture supplying device having, in combination, a liquid container provided with an opening in the lower portion thereof, a moisture absorbing element filling the opening, and means for substantially filling the container with liquid and causing air to be expelled therefrom without disturbing the normal condition of the container whereby the passage of liquid to the moisture absorbing element creates a partial vacuum in the container.

2. A moisture supplying device having, in combination, a liquid container provided with an opening in the lower portion thereof, a moisture absorbing element filling the opening, a conduit connected with the interior of the container for supplying liquid thereto, a conduit leading from the interior of the container for conducting air therefrom, and means for simultaneously opening and closing said conduits.

3. A moisture supplying device having, in combination, a liquid container, a trough connected with the interior of the lower portion thereof provided with an opening, a moisture absorbing element filling said opening, and means for supplying liquid to and conducting air from the container without disturbing the normal position of the container in such a manner that the moisture

supplying device is maintained in a constant state of saturation by moisture supplied from the container.

4. A humidity controlling device of the class described having, in combination, a liquid container, a wet bulb element connected with the container, and means for supplying liquid to and conducting air from the container without disturbing the normal position of the container, in such manner that the wet bulb element is maintained in a constant state of saturation by moisture supplied from the container.
5. A controlling device for controlling the humidity of the atmospheric conditions of a room having, in combination, a liquid container for location at the inner side of a wall of the room, a wet bulb element connected with the container, means controllable at a point at the outer side of the wall of the room without disturbing the normal position of the container for supplying liquid to and conducting air from the container, in such manner that the wet bulb element is maintained in a constant state of saturation by moisture supplied from the container.
6. A humidity controlling device of the class described having, in combination, a liquid container, a conduit leading from the lower portion of the container having its outer end provided with an opening, a wet bulb element filling said opening, and means for supplying liquid to and conducting air from the container without disturbing the normal position of the container in such a manner that the wet bulb element is maintained in a constant state of saturation by moisture supplied from the container.
7. A humidity controlling device of the class described having, in combination, a liquid container, a wet bulb element connected with the container, two conduits leading from the upper portion of the container for supplying liquid to the container and for conducting air from the container, re-
- spectively, in such a manner that the wet bulb element is maintained in a constant state of saturation by moisture supplied from the container, the air conduit opening directly into the atmosphere, and means for opening and closing said conduits.
8. A humidity controlling device of the class described having, in combination, a liquid container provided with an opening in the lower portion thereof, a moisture absorbing element tightly fitting the opening to act as a stopper for the opening to prevent liquid from flowing through the opening during the filling of the container, and means for filling the container with liquid and causing air to be expelled therefrom without disturbing the normal condition of the container to maintain the moisture absorbing element in a constant state of saturation by moisture supplied from the container.
9. A humidity controlling device of the class described having, in combination, a liquid container provided with an opening in the lower portion thereof, a moisture absorbing element extending into the opening, and means for filling the container with liquid and causing air to be expelled directly from the upper portion thereof without disturbing the normal condition of the container to maintain the moisture absorbing element in a constant state of saturation by moisture supplied from the container.
10. A humidity controlling device of the class described having, in combination, a liquid container, a moisture absorbing element connected with the container, and means controllable at a distance from the container for supplying liquid to and conducting air from the container in such a manner as to maintain the moisture absorbing element in a constant state of saturation by moisture supplied from the container.
